UNITED STATES PATENT OFFICE

159,034

POUNDING TOY

George W. Young, Seattle, Wash.

Application September 20, 1948, Serial No. 148,667

Term of patent 14 years

(CL. D34—15)

To all whom it may concern:

Be it known that George W. Young, a citizen of the United States, residing at Seattle, Washington, has invented a new, original, and ornamental Design for a Pounding Toy, of which the following is a specification, reference being had to the accompanying drawing, forming a part thereof, in which

Figure 1 is a perspective view of a pounding toy, showing my new design;

Figure 2 is a perspective view of the same from the opposite side and from beneath;

Figure 3 is a top plan view; and

Figure 4 is a cross sectional view taken along the line 4—4 of Figure 3, the peg in the cutting plane not being sectioned.

I claim:

The ornamental design for a pounding toy, as shown.

GEORGE W. YOUNG.
